UNITED STATES PATENT OFFICE

145,778

DESIGN FOR A PEN AND PENCIL CASE

Josephine A. Commander, Washington, D. C.

Application November 16, 1945, Serial No. 123,827

Term of patent 3½ years

(Cl. D74—21)

To all whom it may concern:

Be it known that I, Josephine A. Commander, a citizen of the United States of America, residing at Washington, in the District of Columbia, have invented a certain new, original, and ornamental Design for Pen and Pencil Case, of which the following is a specification, reference being had to the accompanying drawing, forming a part thereof.

In the drawing:

Fig. 1 is a perspective view of one side of the pen and pencil case, showing my new design with one of the upper flaps raised.

Fig. 2 is a perspective view of the opposite side of the pen and pencil case to that shown in Fig. 1 with all of the flaps closed.

Fig. 3 is a top plan view of the pen and pencil case, and

Fig. 4 is a bottom plan view of the pen and pencil case.

I claim:

The ornamental design for a pen and pencil case, as shown.

JOSEPHINE A. COMMANDER.
